UNITED STATES PATENT OFFICE.

WILLIAM H. MILLER, OF NEW YORK, N. Y.

SPRING-BOTTOM FOR CHAIRS AND UPHOLSTERY.

SPECIFICATION forming part of Letters Patent No. 608,062, dated July 26, 1898.

Application filed March 19, 1898. Serial No. 674,459. (No model.)

To all whom it may concern:

Be it known that I, WILLIAM H. MILLER, a resident of New York, (Brooklyn,) in the county of Kings and State of New York, have 5 invented certain new and useful Improvements in Spring-Bottoms for Chairs and Upholstery; and I do hereby declare the following to be a full, clear, and exact description of the invention, such as will enable others 10 skilled in the art to which it appertains to make and use the same.

My invention relates to an improvement in spring-bottoms for chairs and upholstery, and more particularly to means for connecting the 15 springs with a support, the object of the invention being to obviate the liability of detachment of the springs from their support, as is liable to occur with prior devices of this 20 character of which I am aware, and to so construct and arrange the springs and support that said springs can be easily, quickly, and permanently attached to the support.

A further object is to provide a device for the purpose stated which shall be simple in 25 construction and which shall be effectual in all respects in the performance of its functions.

With these objects in view the invention consists in certain novel features of construction and combinations and arrangements of parts, as hereinafter set forth, and pointed out 30 in the claims.

In the accompanying drawings, Figure 1 is a view illustrating my invention. Fig. 2 is an 35 enlarged bottom plan view.

A represents a portion of a chair-frame, B the springs, and C a support for the springs. The support C is made of spring-wire and is secured in any suitable manner at its ends to 40 the frame of the chair-bottom. Between its ends the spring-wire support is bent to form a series of loops or enlargements 1, the sides 2 2 of which may be parallel or approximately parallel. The wire at the lower or smaller end of each spring is preferably bent inwardly, 45 so as to form a sort of hook 4. The last convolution at the lower or smaller end of the spring is so formed as to have varying dimensions—that is to say, the said last convolution of the spring has a greater diameter on the line *a a'* and *b b* than on the lines *c c* and *a d*. Thus it will be seen that the loop or en-

largement 1 on the support can enter the lower convolution of the spring freely on the line *a a'* and that the spring can be freely turned to the 55 line *b b*, when the free end of the hook 4 will pass through said loop or enlargement 1. The spring will now be further turned until one side of the loop or enlargement 4 enters the crotch of the hook, which forms a stop there- 60 for, and during this movement of the spring the loop or enlargement 4 will bind against the inner face of the last convolution of the spring, and said loop being made of spring- 65 wire it will be bent slightly near the wire-sup- port C, so that the free end of the loop or en- largement will then be slightly greater in di- ameter than the inner portion thereof. The resilience of the last convolution of the spring 70 B will cause it to tightly hug the loop or en- largement on the support at points in close proximity to its juncture with the wire-sup- port C, and thus the spring will be securely 75 locked to the support without the slightest possibility of detachment, and the connection can, as will be readily seen, be made quickly, 80 easily, and by an inexperienced person.

The support can be so disposed as to cause the loops or enlargements to project upwardly 85 within the lower end of the springs B, as shown to the left-hand side of Fig. 1 of the drawings, or said loops or enlargements may be made to project downwardly through the lower convolution of the spring, as shown at the right-hand side of Fig. 1.

My improvements are very simple in construction, comprise but few parts, are easy to manipulate, and are effectual in all respects in the performance of their functions.

Having fully described my invention, what 90 I claim as new, and desire to secure by Letters Patent, is—

1. In a spring-seat, the combination with a wire-support having loops thereon, of a spring having its lower convolution made of 95 varying diameters, whereby to permit the free entrance of the loop on the support and then bind and clamp the loop when the spring is turned, substantially as set forth.

2. In a spring-seat, the combination with 100 a support composed of spring-wire bent to form loops between its ends, of a spring having its lower convolution so formed as to have varying diameters, whereby to receive a loop

on the support freely and then clamp said loop when the spring is turned, the free lower extremity of the spring being bent to form a hook adapted to receive said loop on the support and act as a stop therefor, substantially as set forth.

In testimony whereof I have signed this

specification in the presence of two subscribing witnesses.

WILLIAM H. MILLER.
